(57) **CLAIM**

(21) Appl. No.: **29/280,032**

The applicant claims the ornamental design for the shoulder holster for portable electronic devices, as shown.

(22) Filed: **May 15, 2007**

DESCRIPTION

(51) **LOC (8) Cl. 03-01**

FIG. 1 shows an elevational view of the new design for a shoulder holster apparatus;

(52) **U.S. Cl. D3/218; D3/222**

FIG. 2 shows an elevational view of the new design, with portable electronic devices illustrated in broken lines as stored and transported in pockets of the shoulder holster;

(58) **Field of Classification Search D3/218,**

FIG. 3 shows a front elevational view of the new design as worn by a user illustrated in broken lines; and,

D3/215, 222–223; 224/192–193, 245, 581–583,

FIG. 4 shows a rear elevational view of the new design as worn by a user illustrated in broken lines.

224/198, 624, 911, 674, 675, 607; D2/627

The portable electronic devices shown in broken lines in FIG. 2 are not part of the design sought to be patented.

See application file for complete search history.
